UNITED STATES PATENT OFFICE.

THOMAS K. OBER, OF PHILADELPHIA, PENNSYLVANIA.

BRAIDING-MACHINE.

No. 795,925

Specification of Letters Patent.

Patented Aug. 1, 1905.

Application filed November 14, 1903. Serial No. 181,166.

To all whom it may concern:

Be it known that I, THOMAS K. OBER, a citizen of the United States, residing at Philadelphia, in the county of Philadelphia and State of Pennsylvania, have invented certain Improvements in Braiding-Machines, of which the following is a specification.

This invention relates to mechanism for weaving circular or tubular braid; and its primary object is to provide an improved machine having an increased speed and a simplified construction.

The nature and characteristic features of the invention will more fully appear by reference to the following description and the accompanying drawings in illustration thereof, of which—

Figure 1 represents a side elevation of a braiding-machine embodying my improvements. Fig. 2 represents a plan view thereof. Fig. 3 represents a sectional view taken on the line 3 3 of Fig. 2. Fig. 4 represents a side elevation of a modified construction. Fig. 5 represents a vertical sectional view of the construction shown in Fig. 4. Fig. 6 represents a horizontal projection, partially in section, of mechanism for shifting the outside thread. Fig. 7 represents a horizontal projection, partially in section, of a modified form of mechanism for shifting the outside thread. Fig. 8 represents a side elevation of a bobbin-carrier adapted for throwing the mechanism for shifting the outside thread, and Figs. 9, 10, and 11 represent successive positions of the inside bobbin-carrying mechanism and means for passing the outside thread.

As shown in the drawings, the frame comprises a base 1, supporting the uprights 2, carrying the braiding-tube 3, through which the braid braided at the point 3' is passed.

The driving-shaft 4, having thereon the driving-pulleys 5, is journaled in the bearings 6 and has fixed thereon the beveled pinion 7, which engages and drives in opposite directions the beveled spur-wheels 8 and 9.

The spur-wheel 8 is fixed to a sleeve 10, which revolves upon the bearing-column 11, supported by the base 1. This sleeve carries and revolves the lower or outside thread-bobbins 12 and the spider or support 13 for carrying the circular or cylindrical track 14.

The spur-wheel 9 is fixed to a shaft 15, which revolves within the bearing-column 11. This shaft carries and revolves the spider or support 16, which carries the mechan-

ism for revolving the upper or inside thread-bobbins 17. Journaled in relation to bearings 18, carried by the spider 16, are the pinions 19, which engage and are driven by a circular rack 20, carried by the bearing-column 11. The pinions 19 engage and drive the pinions 21, fixed on shafts 22, which are journaled in the bearings 23 of the spider. The shafts 22 have fixed thereon the driving-wheels 24, having therein the notches 24'. The wheels revolve in seats 25', formed in the carriers 25, the latter being revolved within the revolving track 14 by the thrust of the wheels in their motion of translation.

The carriers 25 are held to the track 14 suitably by the guides 14' on the track and the shoes 25'', bolted to the carriers and engaging the track, by which the parts are readily assembled or separated and a reliable connection is made.

The threads 12' from the bobbins 12, interwoven at the braiding-point 3' with the threads 17' from the bobbins 17, are carried through the eyes 26 and 27 and thence over the tension devices 28 and through the eyes 29 of the arms or thread-carriers 30, oscillating upon the fulcrums 31. The threads 12' are oscillated by the arms in the slots 32 of the track 14, through which they pass to the braiding-point, so that they are thrown alternately above and below the carriers 25 and the bobbins 17, the movements being timed to permit the notches 24' to pass these threads between the wheels 24 and the carriers revolved thereby.

As shown in Figs. 1, 2, and 3, the arms may be oscillated by means of the pitmen 33, connected therewith by the pivots 34 and with the revolving eccentrics or cranks 35 by the rings 36. The eccentrics are fixed on the shafts 37, journaled in bearings 38, carried by the revolving spider 13, the shafts being revolved in their bearings by the pinions 39, fixed thereon and engaging with the spur-wheel or circular rack 40, carried by the column 11.

As shown in Figs. 4 to 8, inclusive, the arms may be oscillated by the carriers 25, as by means of pins 41, fixed to the arms and extending through slots 42 of the revolving track into position to be engaged by the switch grooves or ways 43, formed in the carriers, the respective entrances to the grooves being at the elevations required for engaging the respective pins when the arms are at the limits of their respective move-

ments and the respective grooves being inclined so as to throw the arms to the opposite positions. To hold the arms in the positions to which they are thrown for shifting the threads until they are reversed by the succeeding carriers, any suitable device may be employed. This may be accomplished, for example, by springs 44, having the connections 45 with the arms and the connections 46 with the toggle-links 47, the latter having therein the slots 48, engaged by pins 41, fixed to the track to permit the necessary longitudinal movement of the link. These springs act to hold the arms against movement until their pivotal connections with their respective toggle-links have passed the dead-centers, when they act to complete the throw of the arms by the thrusting actions they exert thereon through the links, the throw being suitably limited by the length of the slots 42, in which the pins 41 reciprocate, Figs. 4 and 6, or the arms may be balanced approximately on their fulcrums and held by a brake or washer 50, opposing frictional resistance to movement from the positions to which the arms are thrown. (See Fig. 7.)

It will now be understood that the upper and lower bobbins are revolved in opposite directions, the carriers for the upper bobbins moving within the track revolving with the lower bobbins, while the arms for passing the threads from the lower bobbins alternately above and below the upper or inside bobbins are carried with the movable track and are operated in synchronous relation with the upper bobbin-carriers and the notched driving-wheels therefor.

As the carriers for the upper bobbins are, as to their masses, within the cylindrical track, the latter directly opposes the centrifugal action of the former and the binding tendency which obtains in moving carriers on top of a circular track is avoided, for the cylindrical track supports the carriers so as to prevent the twisting tendency that obtains where the carriers are supported upon a track that does not directly oppose the central or resultant centrifugal force.

Having described my invention, I claim—

1. In a braiding-machine, a revolute cylindrical track having slots therein, carriers

revolubly connected within said track, arms fulcrumed on and revolute with said track for reciprocating threads in said slots, and mechanism for revolving said track and carriers and reciprocating said arms in unison, said mechanism comprising notched disks engaging said carriers substantially as specified.

2. In a braiding-machine, a reciprocating thread-carrier and a revolute bobbin-carrier which operates said reciprocating thread-carrier, substantially as specified.

3. In a braiding-machine, a revolute bobbin-carrier having switching mechanism connected therewith and a reciprocating thread-carrier having a device engaged by said switching mechanism to effect said reciprocation, substantially as specified.

4. In a braiding-machine, a revolute bobbin-carrier having ways thereon, and a reciprocating thread-carrier having a projection thereon adapted to be engaged by said ways to reciprocate said thread-carrier, substantially as specified.

5. In a braiding-machine, a revolute bobbin-carrier having ways thereon, a reciprocating thread-carrier having a member adapted to be engaged by said ways to reciprocate said thread-carrier, and means for holding said thread-carrier in the position to which it is thrown, substantially as specified.

6. In a braiding-machine, a track, a bobbin-carrier revolubly connected to said track, a reciprocating thread-carrier revolute with said track and having a member adapted to be engaged by said bobbin-carrier to effect said reciprocation, and mechanism for driving said bobbin-carrier relatively to said track, said mechanism permitting the passage of a thread from said reciprocating thread-carrier between said bobbin-carrier and driving mechanism, substantially as specified.

In testimony whereof I have hereunto set my hand, this 12th day of November, 1903, in the presence of the subscribing witnesses.

THOMAS K. OBER.

In presence of—

JOHN THIEL,
UTLEY E. CRANE, Jr.
